Application July 25, 1932, Serial No. 624,372

7 Claims. (Cl. 240—78)

This invention relates to a lighting fixture adapted for fully indirect lighting for producing a strong substantially uniform illumination upon a diffusing surface, e. g., the ceiling of a room, whereby a shadowless, soft illumination will be had at the working level.

It is an object of this invention to provide a lighting fixture which is simpler and more economical to construct, and which will be capable of satisfying aesthetic treatment, and which will produce a uniform, highly efficient illumination of a room in which it is used.

In the accompanying drawings I have illustrated by way of example a preferred form of my invention.

Fig. 1 is a vertical sectional view;

Fig. 2 is a bottom plan view partly broken away, and

Fig. 3 is a view in elevation and partly in section of another form of the invention.

Fig. 4 is a diagram showing a side by side comparison of a photometric curve of the lamp and reflector with a cross-section of a bowl or shield shaped according to my invention.

In these drawings I have shown a fixture supported from the ceiling by a swivel support 10 adapted to permit the lamp always to assume a vertical position. To this swivel is secured a thin tubular shaft 11, adapted to carry the electrical conductors therein; and onto the bottom of this shaft is secured a supporting block 12, to which a lamp socket 13 is secured by means of screws 14.

A number of holes 15 are drilled, preferably vertically, into the top of the supporting block 12, and preferably radial grooves 16 lead from these holes to the bottom edge of the block 12. Suspension members 17, having their ends bent to fit into the grooves 16 and the holes 15, are positioned therein and are secured against withdrawal from the block 12 by means of a husk 18, preferably of sheet metal. A collar 19 is secured to the shaft 11 above the husk 18 to prevent sliding of the husk thereon. This collar is preferably secured to the shaft by means of a set screw.

The lower ends of the suspension members 17 are bent into U-form as shown in the drawings, and engage a ring 20. Preferably the members 17 are of stiff wire, and the ring 20 is radially grooved to accommodate the U-ends of the wire 17 and to hold the wires circumferentially spaced.

A bowl 21 having a central opening 22 rests on the ring 20 and is substantially free from other

support. This bowl may be opaque, e. g. metal, translucent, e. g. opalescent glass, or transparent, or may include stencils or figures of various kinds, but I do not intend this bowl to serve as a reflecting member, but rather as a shield to intercept glare from the lamp and hide the lower end of the supporting part of the fixture.

In the form of the invention shown in Figs. 1 and 2, the bowl 21 may advantageously be of a light-permeable material, preferably a translucent material, and a lamp bulb 23 inserted in the socket 13 extends through the opening 22 and is provided with a reflector 24 which, in the preferred form, may be a metallic film deposited directly upon the bulb itself. The upper part 15 of this lamp above the reflector is preferably frosted as shown in the drawings, to provide a diffusing surface and to avoid sharp shadows on the ceiling and on the bowl 21. This reflector 24 will, in the case illustrated in the drawings, extend approximately to the level of the filament 20 so that the photometric curve of the lamp will start approximately horizontal, except for the short steep downward slope immediately adjacent the edge of the reflector, and gradually curve upward. By photometric curve, I mean the surface 25 along which there will be an arbitrarily low intensity value of light. The shape of the bowl 21 is such that it approximates this photometric curve, and if light-permeable, the bowl preferably may be shaped so that it encroaches very slightly and gradually upon the curve so that it will be uniformly luminous or glowing, or with a uniformly increasing or decreasing intensity, and also so that there will be only a relatively insignificant proportion of the total light fall upon the bowl. This bowl is not intended for reflection, and when it is designed to receive light at all, it is primarily for the prevention of glare, and for the aesthetic effect produced by the soft 30 illumination of the transparent or translucent material, caused by intercepting this glare or spill light.

In Figure 4, I have shown by means of a light distribution curve 35, the corresponding 45 photometric curve 36 and the cross section of a shield 21a how the shield is shaped to approximate the photometric curve of the lamp and reflector. The curve 35 represents light distribution expressed in apparent candlepower at ten 50 feet from the center of the lamp for a 200 watt clear gas filled lamp silvered on the bottom of the bulb to the level of the filament. This curve and the data from which it is drawn are generally available for all commercial lamps. The 55

curve 36 is derived from the curve 35 by calculating at the various angles the distance for equal illumination. Obviously the photometric curve may be derived with greater accuracy by 5 actual measurements with the lamp and reflector of the equal intensity distance for various angles. 21a shows how a shield may be designed to follow the photometric curve according to my invention. Polar coordinates are used in this figure to 10 assist comparison. The radial scale at 120° represents inches for the curve 36 and the shield 21a, and the scale at 180° represents for the curve 35 apparent candle power at ten feet.

The ring 20 which is shown in the drawings as 15 annular, to permit the projection therethrough of the end of the lamp 23, need not be in this or any particular form, and if the lamp bulb is mounted above the ring or the bowl 21, the ring 20 may be solid so as to completely cover the 20 central opening in the bowl. Also the particular manner of connecting the suspension member 17 to the ring, although advantageous, is not essential to other features of my invention. Where 25 an external reflecting member is used over the lamp 23, this may be integral with the ring 20 or may be connected thereto, and some of the advantages of my invention may be utilized even though the lamp 23 should be placed above the bowl 21, in which case a solid circular 30 piece instead of the ring 20 may be used and may afford the principal reflecting surface. I have found it much more advantageous, however, to utilize the bottom of the lamp as the reflecting surface, and to coat this portion of the lamp 35 with a reflecting material, e. g., silver, as already described above.

If the reflecting surface extends above or below the filament, the photometric curve of the lamp and reflector will be changed, and in such 40 case, preferably the curve and/or position of the bowl will also be changed to conform to said photometric curve. Thus the bowl may be nearly flat, or may extend downwardly from the lamp, or may extend upwardly, depending upon the 45 reflector and its relation to the filament of the lamp.

In the form of the invention illustrated in Fig. 3 reflecting shields 30 and 31 which may be of 50 an opaque material, e. g. a satin finish metal, take the place of the shield 21 shown in Figs. 1 and 2. The total encroachment of this shield upon the photometric curve of the lamp with its reflector 24 may be the same as that of the bowl 21. In this case, however, the light which 55 is allowed to fall on the shield 30 all escapes beneath it and the shield is raised above the edge of the reflector 24 just enough to assure the escape of the desired amount of light. The curve of the under side of the shield 30 is designed so 60 that it gradually intercepts throughout its radius the light which has escaped beneath its inner edge.

The ring 31 is a supplementary shield which 65 serves merely to intercept glare from the slit beneath the inner edge of the shield 30. The ring 20 may be integral with this ring 31 or may be omitted, the ring 31 being drilled for reception of the short ends of the wires 17, or other suitable means.

The effect produced by this embodiment is 75 quite similar to that produced by the embodiment of Figs. 1 and 2. In both substantially the entire light is directed upwardly and outwardly without obstruction while only a small component

of light, too nearly horizontal to be important at the working level, falls upon the glare shield for the purpose of illuminating the shield. The downward component of light from these fixtures is less than 10 per cent and may be, and preferably is, less than 5 per cent. 5

Although I have shown and described above a preferred form of my invention, it will be understood by those skilled in the art that this is capable of numerous variations and modifications, in all of which the characteristic simplicity of design and structure, economy of cost and operation may be achieved in a similar manner to that disclosed herein. All such modifications and variations are to be regarded as within the scope 15 of the present invention.

What I claim is:

1. A lighting fixture comprising a tubular supporting shaft adapted to carry electrical conductors, a supporting block secured to the bottom of 20 said shaft provided with vertical holes in its top and radial grooves leading therefrom down the sides at spaced points about said shaft for reception of suspension wires, a lamp socket secured to the bottom of said supporting block, a lamp 25 mounted in said lamp socket having the portion of the glass thereof below the level of the filament silvered to provide a spherical reflector, a plurality of suspension wires each having its ends turned back to a U shape, the upper ends being 30 inserted in the spaced holes of the supporting block and the lower ends lying close to the bulb of said lamp slightly below the upper border of the silvered portion, a ring held in the bottom U's of said wires, a light-permeable bowl 35 supported on said ring and having a central opening approximately the size of the central opening in said ring adapted to permit the lamp bulb and the suspension wires to project therethrough, whereby the silvered portion of the bulb 40 forms a visible part of the fixture when viewed from below, said bowl being shaped to follow approximately the photometric curve of the lamp, whereby the bowl will be uniformly illuminated, but will intercept only a very small proportion 45 of the light from the lamp, a husk slideable on said shaft adapted to fit over the supporting block and lamp socket so as to hold the suspension wires, the holes and grooves of the supporting block, and a fastening means adapted 50 to secure said husk in position upon said shaft.

2. A lighting fixture comprising supporting means, a block secured to the end of said means with holes extending into the block from its exposed surface and radial grooves extending for 55 a substantial distance from said holes, a lamp socket secured beneath said block, suspension members of sufficient rigidity to support their load without objectionable bending, one end of each member being inserted in one of said holes and its adjacent portion held in position by said connecting groove, a husk secured over said block and fitting thereto so as to prevent withdrawal of said suspension members from said block, and a decorative fixture supported by the suspension members. 60

3. An indirect lighting fixture of the type which comprises a lamp, a reflector in substantially dust tight relation to the lamp and adapted to reflect substantially the entire downward component of light from said lamp outwardly and upwardly therefrom, said lamp and its reflector giving a range of high intensity at angular levels in which the light passes from all parts of the filament both directly and by reflection from 75

said reflector and a border range immediately below the range of high intensity in which the light intensity is rapidly diminished, and glare shielding means surrounding said lamp and reflector, which is characterized by having the glare shielding means extended from said reflector into, but not above the angular level at which the intensity of light from the lamp and its reflector is equal to the average of the intensities in said range of angular levels which are exposed to unobstructed direct and reflected radiation from the entire filament and adapted to intercept light of said border range and to diffuse such light as soft illumination from a lower surface of the shielding means and by having the glare shielding means spaced slightly above the rim of the reflector and positioned so that a substantial part of the low intensity light of the border range passes beneath the shield, and by the shielding means being curved gradually over the entire angular range included between the rim of the reflector and the inner edge of the shield, whereby to intercept at its lower surface from its inner to its outer edge light which comes from the lamp at progressively lower angles and thereby to produce a soft illumination thereon.

4. A lighting fixture for use in a room which comprises an electric lamp having a light source and a light permeable envelope, an opaque concave reflector fitted about a portion of the envelope and adapted to reflect back and outward the light which falls thereon from the light source, a light shield having a central opening through which projects the reflector and a portion of the lamp about which the reflector is fitted, its inner edge spaced a short distance from the edge of the reflector and extending from said inner edge a distance sufficient to intercept glare to the eye level of the room from the portion of the lamp beyond the shield but lying entirely within the range of angular levels in which light from the lamp and reflector considered as a unit is less than the full intensity attained at levels beyond the shield, and a supplemental glare shield narrower than the first positioned closely about the reflector, spaced from the first-named shield to allow passing of light there-between for illumination of its surface and ex-

tending from said inner edge a distance sufficient to intercept direct passage of light from the lamp to the eye level of the room through the space between the lamp and the first-named shield.

5. A lighting fixture as defined in claim 4 in which the supplemental shield is curved across the path of light escaping between the reflector and the first-named shield and is adapted to deflect such intercepted light onto the darker surface of said shield.

6. An indirect lighting fixture for a room, which comprises a lamp and a concave reflector surrounding the end of the lamp to reflect outward and upward the downward component of light from the lamp, an annular opaque shield surrounding the lamp near the edge of the reflector, lying substantially entirely below the angular level at which an appreciable part of the illumination at the eye level of the room can come from the lamp by a single reflection from the ceiling and extending above the angular level at which light may pass from the lamp to the eye level of the room without reflection from the ceiling and a supplemental shield below the first-named shield and covering and extending beyond the opening therein sufficiently to prevent passage of light through said opening directly to the eye level of the room but adapted to permit light from the lamp to pass beneath the inner edge of the first-named shield to illuminate its lower surface.

7. An indirect lighting fixture adapted to illuminate a diffusing surface in a room, comprising a lamp and electrical connections therefor, a concave substantially opaque reflector associated with said lamp adapted to throw outward and upward the light radiated downward by said lamp, a shield surrounding said lamp near but spaced from the rim of said reflector whereby to receive on its under side a small amount of outwardly directed light whereby it will glow with a reflected light of low intensity, and a supplemental shield closely surrounding the reflector and covering the space between it and the first-named shield whereby to prevent glare therefrom.

THEODORE L. HOWELL.
